CLAIM

The ornamental design for a steam cooker appliance, as shown and described.

DESCRIPTION

FIG. 1 is a front perspective view of a steam cooker appliance of the present invention.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is bottom plan view thereof.

1 Claim, 7 Drawing Sheets
